US0D1108051S

(12) **United States Design Patent** (10) **Patent No.:** **US D1,108,051 S**
(45) **Date of Patent:** **** Dec. 30, 2025**

(54) **ANTI-WRINKLE APPLIANCE**

- (71) Applicant: **Triple A Finance GmbH & Co. KG**,
Bielefeld (DE)
- (72) Inventors: **Seung Keun Kim**, Jersey City, NJ
(US); **Jang Kyung Jo**, Irvine, CA (US);
Caleb Hunter, New York, NY (US);
Rundong Wang, Brooklyn, NY (US);
Patric Moammer, New York, NY
(US); **Lucas Lehman**, Brooklyn, NY
(US)

(**) Term: **15 Years**

(21) Appl. No.: **29/971,228**

(22) Filed: **Nov. 1, 2024**

Related U.S. Application Data

- (62) Division of application No. 35/517,971, filed on Aug. 4, 2022 (U.S. filing date under 35 U.S.C. 384), and having an international filing date of Aug. 4, 2022.

(57) **CLAIM**

The ornamental design for an anti-wrinkle appliance as shown and described.

DESCRIPTION

8.1 is a front right perspective view of an anti-wrinkle appliance showing our new design;

8.2 is a front view thereof;

8.3 is a left view thereof;

8.4 is a back view thereof;

8.5 is a right view thereof;

8.6 is a back perspective view thereof;

8.7 is a bottom view thereof;

8.8 is a bottom back perspective view thereof;

8.9 is a top view thereof;

8.10 is a bottom front perspective view thereof; and,

8.11 is a right perspective view thereof.
